PUNCH FOR PERFORATING SHEET METAL

Chester Scull, Philadelphia, Pa., assignor to Edward G. Budd Manufacturing Company, Philadelphia, Pa., a corporation of Pennsylvania

Application January 3, 1940, Serial No. 312,214

9 Claims. (Cl. 164—124)

This invention in general relates to punches and more particularly to a punch designed and adapted for perforating special alloy metal such as stainless steel.

5 The principal object of the invention is to provide an improved punch of a design and construction adapted to facilitate the clean cut perforation of sheet metal and to retain the sharpness of its cutting face over comparatively long periods of time.

10 Another object of the invention is to provide a sheet metal punch of the kind indicated, and having an improved arrangement of perforating instrumentalities upon its cutting face.

15 A further object is to provide a punch suitable for perforating sheet metal, such as steel, and having a cutting face of a type particularly adapted to cleanly and effectively perforate such metal and be capable of ready retraction from 20 the aperture created thereby.

With these and other objects not specifically referred to, the invention resides in the combination and arrangement and in the detail of construction as hereinafter set forth, and will 25 be best understood when taken in connection with the accompanying drawing wherein:

Fig. 1 is a sectional view, partly in elevation, disclosing a punch embodying the invention, and operatively retained in a punch head in position 30 to perforate material on an adjacent anvil;

Fig. 2 is a perspective view of the punch;

Fig. 3 is a bottom plan view of the cutting face of the punch;

Fig. 4 is an enlarged, fragmentary, longitudinal 35 sectional view, taken on the line and as viewed in the direction of the arrows 4—4 of Fig. 3; and

Fig. 5 is a view similar to Fig. 4, taken on the line and as viewed in the direction of the arrows 5—5 of Fig. 3.

40 Referring now to the drawing wherein similar characters of reference indicate corresponding parts in the several views of the preferred form of the invention, the letter A designates the punch head or holder of a conventional type power press, and B a punch embodying the features of the present invention and adapted to be operatively secured in the punch head A. The material to be operated upon, in the present instance, a sheet of steel 9, is placed on an anvil 45 or die C having the hole 10 which receives the stem of the punch A and the perforated material.

The punch B, which is preferably composed of steel, comprises an enlarged shank 11, having 50 a recess 12 which accommodates the set screw

or other fastening means (not shown) of the punch head A, and by which the punch is secured to the latter. The shank 11 has an annular flange or shoulder 13 the upper surface of which is adapted to normally seat against the bottom of the punch head (Fig. 1), while the bottom of the said flange is tapered as at 14, and merges smoothly into the stem 15 which terminates in a hardened cutting or shearing face, designated generally at D.

10 The design and general mechanical principles of the cutting face D which embodies the distinctive features of this invention, may be better understood by considering the said cutting face as being divided into two halves by either 15 of the sectional lines 4—4 or 5—5 of Figure 3. The half, for example, on the lower side of the sectional line 5—5, has a smoothly shelving or sloping surface in angular relation to the vertical axis of the stem 15, this sloping surface being defined by a sector S which is circumscribed by the radii 16, 17 and their subtended arc 18, which latter forms one of the two comparatively large, angularly-positioned, arcuate cutting or shearing edges of the cutting face D. The remaining portion of this half of the cutting face 20 D is occupied by a smaller sector or facet S², the surface of which lies in a plane angularly positioned with respect to the plane of the larger sector S and with respect to the vertical axis of 25 the stem 15 of the punch. The plane surface of the facet S² is defined by the common radius 17, the radius 19 and the comparatively small arc 21, the latter forming an auxiliary or second shearing or cutting edge which coacts with the 30 cutting edge or arc 18 to complete one-half of the shear of the material to be cut; the shearing of the other half being effected by a similar arrangement of sectors with corresponding 35 shearing edges on the other half of the cutting 40 face D now to be described.

The other and similar half of the cutting face D as indicated above, has a sloping surface in angular relation to the vertical axis of the stem 45 15, as defined by the sector T which is circumscribed by the common radius 19, the radius 22, and the subtended arc 23, the latter forming the other large, angularly-arranged, arcuate cutting edge of the cutting face of the punch. The remaining surface of the instant half of the cutting face, as in the other half above-described, takes the form of a small sector or facet T² whose surface is in angular relation to the vertical axis of the stem and to the plane of the larger sector T. The facet T² is circumscribed by the two 50 55

common radii, 16, 22 and the small arc or arcuate cutting edge 24. The relative lengths and slopes of the cutting arcs or edges on each half of the cutting face, it is evident, will determine 5 the character and the extent of the progressive cut afforded by each cutting edge.

As best shown in Figs. 2 and 5, the broken line 25 which divides the cutting face into equal halves, and formed by the juxtaposition of the 10 facet S² and sector T on one side; and the facet T² and sector S on the other side, provides a comparatively sharp, compound ridge or edge, each half of which slopes centrally downwardly to the axis of the stem 15 or the center of the cutting 15 face D where it joins and forms a continuation of the other half. This ridge, which may be considered the dividing line between the two halves of the cutting face, ascends from the said centre or axis to join the junction of the arcs 18, 21 20 and 23, 24 where, in conjunction with the adjacent facets and sectors, it forms salient points or perforating projections 26, 26' which may be considered as pilots to facilitate the initiation of the progressive cutting or shearing action of the 25 punch in operation.

In practice, the action of the instant punch may be readily comprehended by comparison with a punch having a uniformly flat end. In this latter case, it is evident the pressure essential to 30 perforate the material will be applied equally and simultaneously about those portions of its periphery in contact with the punch. In contradistinction to this action, in the case of the punch B, it will be observed that the pilots or projecting points 26, 26' will initially pierce or form a small hole in the material at diametrically opposite points and with but a fraction of the force 35 required to effect a complete perforation.

This initial piercing action is immediately followed by a partial division or initial slight splitting of the disc of material from the points of 40 initial perforation and in coincidence with the center line or ridge 25 which maintains progressive contact with the material. Simultaneously 45 with this action, a smooth, progressive shearing or cutting action of the larger, arcuate, angularly-positioned cutting edges 18 and 23 from continuously opposite points of the periphery of the cutting face D, takes place. This last described 50 action is supplemented by the substantially synchronous shearing action of the two facets S² and T² or small arcs 21 and 24 which complete the cutting of the two comparatively small portions 55 of the material not cut by the larger sectors or cutting edges 18 and 23.

The angle *a* between the inclined surface S or T respectively and a plane *y* which is perpendicular to the axis *x* of the punching tool B, is comparatively small as indicated by Fig. 4 of the 60 drawing. This angle *a* may be of the order of about 15°. The angle *b* between the plane *y* and the surface T² or S² respectively is considerably greater, as shown in Fig. 1, and it may be of the order of about 50° to 60°. The relation between 65 the angles *a* and *b* is, therefore, in the order of about 1 to 4. The end view shown in Fig. 3 indicates that the surface S covers a sector which is about five times as great as the sector covered by the adjoining surface portion S².

70 The inclination of the surfaces S and T runs parallel to the radial lines 17 and 22 respectively, thereby facilitating the grinding of these surfaces. The inclination of the surfaces S² and T² runs about vertical to the radial lines 19 and 16 75 respectively.

The entire operation of perforating a section of material, it is understood, takes but a fraction of a second, but has been herein described as considering the punch as slowly moving, by comparatively small increments, against and through 5 the material.

It may be further pointed out that by reason of the initial piercing and partial splitting of the material and the further progressive action of the present punch, the entire perforating action 10 is facilitated, made smoother and less noisy, the action being markedly conducive to the long life of the punch and the power press, and the general comfort of the operator. In addition to this by reason of the initial splitting of the material al- 15 luded to above, the stem of the punch is less prone to bind in the anvil and/or have its shearing blunted, as in punches having uniformly flat or uniformly concave cutting faces.

It is to be understood that the invention may 20 be embodied in other specific forms without departing from the spirit or essential attributes thereof, and it is therefore desired that the present embodiment be considered in all respects as illustrative and not restrictive, reference being 25 had to the appended claims rather than to the foregoing description to indicate the scope of the invention; and it will be further understood that each and every novel feature and combination 30 present in or possessed by the mechanism herein disclosed, forms a part of the invention included in the application.

What I claim is:

1. A punch of the character described, comprising, in combination, a body portion, a cutting 35 face arranged on one end of the body portion, a median line dividing the cutting face into two halves, each of said halves being similar and having a pair of cutting instrumentalities, one of the instrumentalities having a comparatively long 40 arcuate edge, the other cutting instrumentality having a comparatively short arcuate edge, and a ridge coincident with the median line and serving as a piercing agency independently of the arcuate cutting edges.

2. A punch of the character described, comprising, in combination, a stem, a cutting face arranged on an end of the stem and having two similar half portions, each of the half portions including a pair of coacting surfaces, one of the 50 surfaces being a comparatively large sector of the half portion, the other of the surfaces being a comparatively small sector of the half portion, cutting means arranged on both of said surfaces and piercing means arranged on a median line 55 dividing the two half portions.

3. A punch of the character described comprising, in combination, a cylindrical member, a cutting face arranged on an end of the member, a pair of cutting means arranged on each half 60 portion of the said face, one of said cutting means having an arcuate edge whose plane is arranged in substantial angular relation to the axis of the said member, and having a second arcuate edge whose plane is positioned in angular relation to 65 the first mentioned arcuate edge and to the said axis, and piercing means common to both of said half portions and arranged therebetween.

4. A punch of the character described and wherein each half of the cutting face of the punch 70 progressively completes one-half of a perforating operation, comprising an elongated member, a cutting face arranged on an end of the member and having a pair of bevelled surfaces on each half portion thereof, said surfaces being angular- 75

ly positioned with respect to each other and inclined relatively to the vertical axis of the member, one of the bevelled surfaces providing a comparatively long arcuate cutting edge, the other 5 of the surfaces having a comparatively short arcuate cutting edge, and piercing means common to the bevelled surfaces of both of said half portions and adapted to facilitate the initiation and progress of a perforating operation.

10 5. In a tool for punching holes, a shank, a cutting edge at one end of said shank and along the outer surface thereof, said cutting edge comprising adjoining portions which are oppositely inclined relative to the axis of said shank, one of 15 two such adjoining portions being comparatively slightly inclined relative to a plane which extends perpendicular to the axis of said shank, and the other portion being considerably more inclined relative to such plane.

20 6. In a tool for punching holes, a shank, the outer surface of said shank which is coextensive with the axis thereof, and one of the end surfaces of said shank forming together a cutting edge, said end surface comprising pairs of portions 25 which are inclined relative to a plane which extends perpendicular to the axis of the shank, the relation between the inclination angles of the two surface portions of one pair being in the order of about 2 to 7.

30 7. In a tool for punching holes, a shank, the outer surface of said shank which is coextensive with the axis thereof, and one of the end surfaces of said shank forming together a cutting edge, said end surface comprising pairs of portions 35 which are inclined relative to a plane which ex-

tends perpendicular to the axis of the shank, the inclination angles of the portions of a pair of surface portions being in the order of about 15° and 55° respectively.

8. In a tool for punching holes, a shank adapted to be moved in the direction of its axis, the outer surface of said shank which is coextensive with the axis thereof and one of the transverse end surfaces of said shank forming together a cutting edge, said end surface comprising pairs of adjoining surface portions, one surface portion of such pair being inclined in one direction relative to the axis of the shank, and the second surface portion of the same pair being inclined relative to the axis of said shank in another direction, the directions of inclination of the surfaces including an angle of less than 90° when viewed in the direction of the axis.

9. In a tool for punching holes, a shank adapted to be moved in the direction of its axis, the outer surface of said shank which is coextensive with the axis thereof and one of the transverse end surfaces of said shank forming together a cutting edge, said end surface comprising pairs of adjoining surface portions, one surface portion of such pair being inclined in one direction relative to the axis of the shank, and the second surface portion of the same pair being inclined relative to the axis of said shank in another direction, the directions of inclination of the surfaces including an angle of about the order of 90° when viewed in the direction of the line of intersection of two surface portions belonging to one pair.

CHESTER SCULL.
